UNITED STATES PATENT OFFICE.

HERBERT H. MILLS, OF CHICAGO, ILLINOIS.

PERMANENT BINDER FOR PAPER SHEETS.

1,372,161.

Specification of Letters Patent.

Patented Mar. 22, 1921.

Application filed September 20, 1920. Serial No. 411,609.

To all whom it may concern:

Be it known that I, HERBERT H. MILLS, a citizen of the United States, and resident of Chicago, in the county of Cook and State 5 of Illinois, have invented certain new and useful Improvements in Permanent Binders for Paper Sheets, of which the following is a specification.

My invention relates to binders and particularly to a novel device adapted to permanently secure a quantity of sheets between binder covers.

The general objects of my invention are to provide simple and relatively very economical means for securing the desired result, the idea being to employ a device of this kind as a form of transfer binder in which sheets which are intended to form a portion of a permanent record may be held 20 in their original relation without the possibility of removal. This serves the purpose not only of avoiding the removal and possible loss of records which are intended to be permanent but avoids the expense of binding such records as is the practice at the present time.

A specific object is to provide a device of this kind which may be operated by unskilled or inexperienced clerks without the 30 possibility of error.

The invention will be more readily understood by reference to the accompanying drawings, wherein,

Figure 1 is a perspective view of the different parts constituting the device of my invention;

Fig. 2 is a fragmentary vertical sectional view through a binder with which my improvement is associated, and,

Fig. 3 is a plan view of the locking element, the binding posts being shown in section.

In the drawings it will be seen that I may provide upper and lower boards or covers 45 10, 11, each thereof carrying U-shaped members, the legs 12, 12 and 13, 13, of which project through suitable openings in the covers, the intermediate portions 14, 15, lying on the outside of the covers. In the 50 drawings I have illustrated the posts as of rectangular cross section although they may be of other shapes as for instance, semi-circular. The legs or posts 12, are provided with notches or teeth 15, on their outer surfaces near the ends thereof, while the posts 55 13 are provided with similar teeth or

notches 16, on their inner surfaces. When the posts are mounted in back-to-back relation, as shown in Fig. 2, the notches on the respective posts appear on the outside. 60

As to the locking element, I provide a thin, flexible steel strip 17, having apertures 18, near the ends thereof and suitably spaced to register with the posts. The apertures are so positioned that the distance between the extremities thereof is slightly less than the normal distance between the outer extremities of the posts 12. Projecting into the apertures 18 are tongues 19, formed by suitably slitting the strip, and the distance 70 between the extremities of the tongues is slightly greater than the normal distance between the posts 13. In practice one of the cover boards is filled with sheets up to substantially the limit of the binding posts. 75 The locking strip 17 is then forced over the posts and pressed down. If the board 11 is first filled with sheets the metal adjacent to the apertures in the strips will engage with the notches on the outer surfaces of 80 the binding posts and temporarily hold the sheets in position. The other cover board is then filled with sheets to the desired limit and the posts are inserted in the apertures 18 in the strip, this necessitating the bending of the tongues 19 in the direction of movement of the posts to their final position. When the two boards and their associated sheets have been tightly pressed together, the parts will assume the position 90 shown in Fig. 2, from which it will be seen that the covers cannot be separated, the tongues 19 acting as dogs or pawls which prevent the retraction of the notched posts. 95

Furthermore, it will be noted that the locking strip is located in the body of the sheets and cannot be interfered with. By the use of the construction described the sheets may be permanently locked in place and the device for accomplishing the result 100 may be very economically constructed.

Obviously the invention is capable of much modification and I do not wish to be limited except as indicated in the appended claims.

I claim:

1. In a binder, the combination of covers, a post carried by each cover, said posts being adapted to slide past each other and being notched on their outer surfaces, and an 110 apertured locking strip located substantially in the middle of a bundle of sheets

held between said covers adapted to be engaged by the notches in said posts.

2. In a binder, the combination of a pair of covers and posts projecting therefrom, a post in each cover being adapted for sliding coöperation with a post on the other cover, said posts being notched on opposite faces, and an apertured spring-strip provided with a tongue adjacent said aperture, 10 said tongue and the metal of the strip opposite to said tongue being adapted to coöperate with the notches in the posts to permanently lock a bundle of sheets between the covers.

15 3. In a binder, the combination of a pair of cover boards and a pair of posts projecting from each board, the posts on each board being adapted for coöperative longitudinal movement, the outer surfaces of a pair of 20 said coöperating posts being notched or serrated, and a locking strip composed of thin spring-steel having an aperture providing spring-engagement with the notches on said posts, said strip being adapted to 25 permanently lock the boards against separation.

4. In a binder, the combination of a pair of boards, U-shaped members projecting through the boards, the legs of the members 30 acting as posts, the legs of the respective U-shaped members being adapted for coöperative longitudinal movement and being notched on their outer surface, and an apertured spring-metal strip providing 35 a resilient tongue projecting into said aperture, said tongue being adapted to be deflected and to act as a pawl to engage the notches on one of said posts and prevent separation of the posts without destruction of the locking strip.

5. A permanent lock for binders comprising a pair of oppositely projecting posts provided on one side with plane surfaces adapted for longitudinal coöperative movement and on the opposite side with serrations, and a spring-metal strip having an aperture and a tongue projecting into said aperture, the size of the aperture being less than the combined thickness of the posts whereby as the posts are forced into the 50 aperture the tongue is deflected.

6. A permanent locking device for binders, comprising two pairs of posts each post having a plane surface adapted for longitudinal movement on a coöperating post and 55 also provided with serrations on the opposite surface, and a metal strip having apertures spaced apart a distance less than the distance between the outsides of the posts and provided with tongues projecting into 60 said apertures, the width of the apertures being slightly less than the thickness of the coöperating posts whereby the tongue is caused to be deflected as the posts are received within the tongues, the locking strip 65 serving to permanently lock the sheets in place.

7. A binder comprising in combination cover boards, a pair of posts projecting from said boards, said posts being shaped 70 for coöperative relative longitudinal movement, said coöperating posts having notches on their faces, a metal strip having an aperture registering with the posts, said strip being provided with a tongue projecting 75 into the aperture adapted for coöperation with a notched post.

Signed at Chicago, Ill., this 18th day of September, 1920.

HERBERT H. MILLS.
